UNITED STATES PATENT OFFICE.

AZOR R. HUNT AND WILLIAM AHLEN, OF DUQUESNE, PENNSYLVANIA.

HEATING-FURNACE FOR COILED BUNDLES.

SPECIFICATION forming part of Letters Patent No. 699,528, dated May 6, 1902.

Application filed January 28, 1902. Serial No. 91,611. (No model.)

To all whom it may concern:

Be it known that we, AZOR R. HUNT and WILLIAM AHLEN, of Duquesne, in the county of Allegheny and State of Pennsylvania, have invented a new and useful Heating-Furnace for Coiled Bundles, of which the following is a full, clear, and exact description, reference being had to the accompanying drawings, forming part of this specification, in which—

Figure 1 is a top plan view, partly broken away, of a heating-furnace constructed in accordance with our invention. Fig. 2 is a vertical transverse central section of the same. Fig. 3 is a partial vertical section showing the feed-opening and cover. Fig. 4 is a top plan view showing a modified form of furnace, and Fig. 5 is a central vertical section of the form of Fig. 4.

Our invention relates to the heating of bundles of wire, rods, or bars which are in the form of reeled coils; and its object is to provide a continuous furnace in which the coils may be rapidly and economically heated and the heated coils drawn out either continuously or intermittently and fed to the machine operating upon it.

Heretofore manufacturers of rivets, bolts, and spikes, &c., have ordered their material in the form of straight rods of different lengths, as they were unable to heat coiled bundles, and as the end portion of each piece was wasted a considerable loss of material resulted, while handling of the straight lengths was laborious and awkward. Our invention overcomes these difficulties and provides a continuous heating-furnace in which the coiled bundles may be heated and then uncoiled and drawn out directly to the machine without removing the bundle as a whole.

In the drawings, referring to Figs. 1, 2, and 3, in which we show the preferred form of our furnace, 2 represents the circular outer wall, and 3 the concentric inner wall of an annular furnace having an annular cover 4. We have shown the side walls as carried upon angles 5, supported upon posts or standards 6, with stay-bolts 7 connecting the inner and outer posts. The walls and roof are of refractory material, such as fire-brick, and the arched roof rests upon the side walls.

The bottom 8 of the furnace consists of an

annular platform having inner and outer depending flanges 9, resting upon rollers 10 and 11, mounted on shafts 12. Annular water-troughs 13 and 14 project from the edges of the furnace-bottom, and downwardly-projecting flanges or plates 15 project into these troughs, and thus form an air-tight seal for the furnace-chamber. The rotatory bottom is provided with a series of rotatory disks or reels 16, mounted upon central spindles 17 and having annular ball-bearings 18 between them and the bottom. The reels or disks are covered with refractory material, as shown, as are also the surrounding parts of the bottom.

The outlet or stack flue 19 is preferably located adjacent to a depending partition 20, which extends from the inner to the outer end of the furnace, and on the opposite side of the partition are gas and air inlets 21 and 22, and the flame and gases travel around the furnace to the outlet-flue, short-circuiting being prevented by the radial partition. This partition is centrally notched to allow passage of the projecting central portions of the reels, and this notch is provided with a depending hinged door 23 on the outlet-flue side. After the furnace-bottom has been moved so that the boss of the reel passes the door this door immediately swings back into place by gravity and closes the partition.

The furnace is provided with a suitable number of doors 24 in the outer side walls for inspection of the furnace and manipulation of the reels.

In order to distribute the flame evenly over the cross-section of the annular bottom, the inner side wall is preferably made of less height than the outer wall, the roof being correspondingly inclined downwardly and inwardly. The center of cross-section area is thus changed to a point nearer the outer wall, thus distributing the flame toward this outer wall and directing a greater portion of the radiated heat from the roof to the outer portions of the furnace-chamber.

We have shown the outlet-flue as formed in a removable cover-section 25, which may be lifted vertically by any suitable hoisting means, (indicated at 26, Fig. 3.) The coiled bundles are charged in through this opening.

To turn the furnace-bottom any suitable

mechanical connections may be used, and we have shown for this purpose a pivotally-mounted motive cylinder 27, whose piston-rod 28 is arranged to act against vertical angles 5 29, secured to the bottom frame. The motor is held in normal position by a spring 30.

When operating the furnace, each of the disks or reels is covered with one or more bundles of coiled material to be heated, 10 rounding the central boss or projection. During the heating of the coils the bundle at the discharging-point *a* is being drawn out either intermittently or continuously through a hole or slot in the door and fed into the rivet or 15 bolt machines or other point of consumption. During this withdrawal the carrying disk or reel revolves to allow unwinding of the coils. When this coil has been drawn out, the furnace is turned to bring the next reel into this 20 position, and the end of this next coil is then pulled out through this opening and fed to the machine. At the same time the removable roof-section is removed and a cold bundle lowered upon the empty reel, which has 25 passed the separating-partition. The removable roof-section is then replaced and the heating continued until the next coil is withdrawn, these operations going on continuously.

Instead of providing a large annular furnace-chamber through which the flame and 30 gases pass through a circular path we may provide an open circular chamber through which the flame and gases pass transversely to the outlet. Thus in Figs. 4 and 5 we show 35 a circular furnace-chamber having an outer wall 2' and a circular bottom 8', carried on a central spindle 31 and also mounted on a circular roller-bearing 32. The bottom is provided with an outer sealing-trough 13', into 40 which projects a circular plate 15'. The reels or disks 16', of which we show three, are preferably mounted on spindles 17' and ball-bearings 18', as before. The roof 4' is provided with a removable cover 25' on the side adjacent to an outlet-flue 33, leading to a stack 34. The gas and air inlets 21' and 22' extend through the side walls on the side opposite to the outlet-flue. In this form the flame and 45 gases circulate through the furnace-chamber and heat the coils, one of the coils being drawn out through door 35 while the other two are being heated. We have shown the cylinder 27' as arranged to rotate the bottom intermittently, as before.

50 The advantages of our invention result from the heating-furnace for the coiled bundles, in which the bundles are supported by revolute supports on a carrier allowing them to be fed out directly to the machine or point of use. The reeled bundles are more easily handled than rods and will be cheaper for the rolling-mills and for the users of the material. The operation is continuous, and as the gases pass in the opposite direction to 55 that of rotation of the furnace the material passes from cooler into successively hotter

zones, thus applying the heat in the best manner and economizing the fuel.

As there is only one waste end to each entire bundle, the loss is reduced and the continuous furnace increases the output of the machines to which the material passes. 70

Many variations may be made in the form and arrangement of the furnace, the bundle-supports, and the manner of operating without departing from our invention. 75

We claim—

1. A continuous heating-furnace comprising a movable carrier, a set of revolute bundle-supports mounted on the carrier, and a furnace-chamber through which the bundles pass; substantially as described. 80

2. A furnace-chamber having an endless carrier forming its bottom, means for moving the carrier, and a series of revolute bundle-supports mounted on the carrier-bottom; substantially as described. 85

3. A bundle-heating furnace of circular form, having a rotary bottom, and a coacting water-trough, bundle-supports revolutely 90 mounted on said bottom and flange forming an air seal around the furnace; substantially as described.

4. A continuous heating-furnace for bundles, having an annular heating-chamber, a 95 rotary bottom carrying revolute bundle-carriers, and a partition extending transversely of the furnace-chamber and arranged to prevent short-circuiting of the gases; substantially as described. 100

5. A heating-furnace having a fuel-inlet and gaseous outlet, and a rotary bottom, revolute bundle-carriers mounted on said bottom, a radially-extending partition between the fuel-inlet and the outlet for gases, and a 105 door in said partition arranged to be actuated by the bundle-carriers, substantially as described.

6. A continuous heating-furnace having an annular furnace-chamber of smaller cross-sectional area in its inner portions than in its outer portions; substantially as described. 110

7. A continuous heating-furnace having an annular chamber with a rotary bottom, arranged to receive coils, and a roof which is 115 inclined inwardly to contract the cross-sectional area of the inner part of the chamber; substantially as described.

8. A heating-furnace comprising a movable carrier, a set of revolute-mounted bundle-supports on the carrier, and a furnace-chamber through which the bundles pass, said chamber having an opening through which a heated bundle may be uncoiled and drawn; substantially as described. 120

In testimony whereof we have hereunto set our hands.

A. R. HUNT.
WM. AHLEN.
